H. L. CRAIG

TRAIN STOPPING MEANS

Filed March 27, 1922

UNITED STATES PATENT OFFICE.

HARRY L. CRAIG, OF COLLEGE POINT, NEW YORK.

TRAIN-STOPPING MEANS.

Application filed March 27, 1922. Serial No. 546,999.

To all whom it may concern:

Be it known that I, HARRY L. CRAIG, a citizen of the United States of America, residing at College Point, county of Queens, 5 and State of New York, have invented certain new and useful Improvements in a Train-Stopping Means, of which the following is a specification.

This invention relates to improvements in 10 train stopping devices, and one of the objects thereof is to provide new and improved operating means for actuating the emergency brakes of a railroad train, and simultaneously operating the throttle lever 15 to shut off the steam from the cylinders of the engine.

The present invention contemplates certain improvements covered in my Patent 20 No. 1,081,892 issued December 16th, 1913.

Other objects and aims of the invention, 25 more or less specific than those referred to above, will be in part obvious and in part pointed out in the course of the following description of the elements, combinations, 30 arrangements of parts and applications of principles, constituting the invention, and the scope of protection contemplated will be indicated in the appended claims.

In the accompanying drawing, wherein I 35 have illustrated a preferred form of embodiment of my invention:

The figure is a plan view of a preferred embodiment of my invention.

Referring now to the drawing, the reference numeral 1 denotes a lever adapted to 40 control the air in the braking apparatus of a railway train, a portion of such apparatus being indicated at 2. It will be understood of course that this braking apparatus may be of any desired character.

Pivotedly connected at 3 to the lever 1 is 45 a rod 4, which extends through the guides 5 and 6, and positioned upon said rod, and interposed between the guide 6 and a pin 7 carried by the rod, is the coil spring 8, the function of which is to urge the rod in the direction of the cam 9, whereby the valve lever 1 will be held in the position shown in the drawing.

The cam lever 9 is carried upon the arms 50 10 and 11, which approach each other to form the hub 12, the latter being journaled upon the shaft or stud 13. The cam 9 is so tapered longitudinally of its length that 55 when it is moved or falls to the position shown in the dotted lines of the drawing,

its engagement with the end 14 of the rod 4 causes it to push the latter against the tension of the spring 8, whereby the air 60 brake lever 1 will be actuated.

The cam 9 is provided with a notch 15, which receives the downwardly extending part or flange 16 of the bar 17, said bar 65 extending downwardly through the floor of the cab of the engine, and terminating in the head 18.

Mounted upon a fixed pin 19 is the lever 20, having the cam faces 21 and 22, the latter being disposed at a greater distance 70 from the point of pivotal support of the lever 20 than the face 21, whereby when the lever 20 is swung to the position shown in the dotted lines of the drawing, the engagement of the cam face 22 with the head 18 of the bar 17 will cause the latter to raise, thereby lifting the catch 16 out of the notch 15, of the cam 9, whereby the latter will fall by gravity to the position shown in the dotted lines in the drawing, 75 causing the rod 4 to be slid longitudinally and operate the air brake control lever 1.

The lever 20 is intended to be operated by a fixed stop or abutment placed adjacent the railway track, said lever being so positioned with respect to said abutment that when the train passes that point, said abutment will strike the lever and cause it to be swung to the position shown in the dotted lines in the drawing, thereby causing 80 the operation of the air brake lever just described.

Referring now to that portion of my device which operates to shut off the steam, the reference numeral 23 denotes the usual 85 throttle lever, pivotally mounted at 24 to a fixed support, and having pivoted thereto intermediate its ends at the point 25, the valve rod 26, which valve rod at its opposite end is connected with the lever controlling 90 the admission of steam to the cylinder of the engine. This last named part is not shown in the drawing, inasmuch as the construction thereof forms no part of the present invention, it being sufficient for the 95 purpose of this description to understand that the rod 26 actuates the throttle valve 100 of the engine.

The reference numeral 27 denotes an arc-shaped rack mounted upon a fixed support 110 (not shown) as by means of the screws 28 and 29, the teeth 30 of which cooperate with

a dog 31, slidably mounted in a guide slot 32, provided in the lever 23, whereby the latter will be held in any set position.

The dog 31 is constantly urged in the direction of the rack so that its teeth 33 will engage with the teeth 30 of the rack by means of an extensile spring 34, which encircles a rod 35, extending rearwardly from the dog and passing through an aperture formed in a guide post 36, carried by the lever 23.

Pivots 15 mounted to the dog 31 at 37 is a link 38, the latter being pivoted at 39 to the bell-crank lever 40, one leg 41 of which is pivotally mounted at 42 to the lever 23, adjacent the handle 44 thereof, the other leg 45 of the bell-crank lever terminating in a handle portion located adjacent the handle 44, whereby the engineer in grasping 20 the handle 44 can also grasp the handle 45, whereby the bell-crank lever 40 will be swung to withdraw the teeth of the dog from the teeth of the rack, terminating the lever 23 to be swung in either direction upon its 25 pivotal support.

Pivottally mounted upon a post or screw 46, provided upon the dog is a link 47, and the opposite end of said link being pivoted at 48 to a link 49, the latter being pivoted to the stud or screw 25, to which the valve control rod 26 is also pivoted.

Links 47 and 49 form a toggle, which when straightened moves the dog 31 rearwardly to disengage the teeth of the latter from the teeth of the rack, thereby performing the same function as is performed by the manual operation of the bell-crank lever 40.

Referring now to the mechanism employed for automatically straightening the toggle to release the teeth of the dog 31 from the teeth of the rack, the link 49 is provided with a rearward extension 50, the end 51 of which is located in a position to be engaged by the head 52 of the piston rod 53 carried by the piston 54. The piston 54 is mounted in a cylinder 55, the coil spring 56 encircling the piston rod, and interposed between the end wall 57 of the cylinder and the piston 54, operating to move and hold the latter in the position shown in the drawing. It will be understood that if the dog 31 were permitted to slide downwardly indefinitely, the link 47 would be merely swung to the left with no sufficient application of force to the throttle lever 23 to move it adequately, the spring 35 being relatively a light spring. Therefore, as shown, the movement of the dog lengthwise of the lever is arrested by the termination of the guide slot 32, after the disengagement of the dog and the quadrant 27 and prior to the complete alignment of the links 47 and 49. The pressure of the piston rod head 52 thus becomes effective in moving the lever 23 and the throttle valve rod 26.

Leading into the cylinder 55 in front of the piston 54 is a conduit 58, which conduit leads through a valve 59 to a conduit 60, the latter being connected with a source of air pressure not shown.

The valve 59 is operated by a lever 61, the end 62 of which is located in the path of an arm 63 provided upon the air brake operating rod 4, so that when said rod 4 is moved in an endwise direction, as already described, said arm 63 engaging the end 62 of the lever 61, will operate said last mentioned lever to open the valve 59 so that the air pressure exerted through the conduit 58 upon the piston 54 will cause the latter to be moved in the cylinder 55, whereby the head 52 of the piston rod will engage with the extension 50 of the link 49, thereby straightening the toggle and disengaging the teeth of the dog 51 with the teeth of the rack. The continued movement of the piston rod in an outward direction under the air pressure will, when the toggle 50 is straightened, cause the throttle lever 23 to be swung to the right, thereby moving the valve rod 26 longitudinally to operate the throttle valve and shut off the steam.

The spring 56, which is employed to return the piston 54 to the position shown in the drawing, when the pressure in the conduit 58 is released by means of a suitable vent not shown, is of tapered form, so that the convolutions thereof will nest together when the spring is compressed. 95

It will accordingly be seen that I have provided a construction well adapted to attain, among others, all the ends and objects above pointed out, in a simple yet facile manner; whereby the emergency braking mechanism of a railway train and the throttle valve of the engine may be simultaneously operated. 100 105

Having thus described my invention what I claim as new and desire to secure by Letters Patent is:

1. In train stopping means, the combination with releasable latched devices, of a spring controlled air brake rod actuated by the release of the said devices, the said rod having a striker arm projecting from it, an air valve arranged to be operated by the movement of the said arm, a cylinder having a spring controlled piston and piston rod, the cylinder being in communication with the said air valve, a throttle valve lever, a toothed quadrant, a releasable dog carried by the said lever and engaging the quadrant, a throttle valve rod pivotally attached to the said lever, a toggle joint having a limited movement and having the end of one link attached to the said dog, and having an intermediate point of the second link of the said toggle pivotally attached to the connection of the said lever and throttle valve rod, and the free extremity of the said second 115 120 125 130

link being arranged in the path of and operated by the said piston rod whereby the said dog is released and the said throttle valve rod is moved.

5 2. In train stopping means, a throttle valve lever, in combination with a throttle valve rod pivotally attached to the lever, a toothed quadrant, a dog mounted to slide upon the lever and engaging the quadrant, 10 means for releasing the dog comprising a toggle joint having the end of one link connected with the dog, and an intermediate point of the second link of the toggle pivotally attached to the said lever, means for

limiting the release movement of the dog 15 after its disengagement from the quadrant and prior to the complete alignment of the links of the toggle, and a fluid operated piston rod arranged to act upon the free end of the said second link of the toggle whereby 20 the toggle joint and the throttle valve lever are operated.

In testimony whereof, I affix my signature in the presence of two witnesses.

HARRY L. CRAIG.
